TRAIN CONTROL SYSTEM

Original application filed November 10, 1926, Serial No. 147,403. Divided and this application filed June 21, 1929. Serial No. 372,567.

This invention relates to train control systems, the train controlling means being train-carried signals, and/or retarding or stopping devices, and has for its main object and feature to suitably correlate trackway and train equipment in a simple and effective manner.

This application is a division of application Ser. No. 147,403, filed November 10, 1926.

In the accompanying drawings the invention is disclosed by way of illustration, but not limitation, in a concrete and preferred form in which:

Fig. 1 is a diagrammatic view of a typical trackway equipment that may be used in connection with the invention;

Fig. 2 is a diagrammatic view of a preferred form of train-carried equipment;

Figs. 3 and 3a are diagrammatic views of a characteristic curve of an electron tube showing the manner in which said characteristic curve can be used in carrying out the invention;

Fig. 4 is a diagram illustrating the variations of the trackway current; and

Figs. 4a and 4b are diagrams illustrating the effect of the variations of Fig. 4 on the plate current of the train-carried electron tube under different operating conditions.

E indicates a train-carried electron tube detector, having a plate P, a grid G and a filament F, said tube having associated therewith a grid-filament circuit and also a plate-filament circuit having a current source. In this invention it is proposed to effect the control of the train by varying the average value of the current flow in the plate-filament circuit and to do this by controlling the potential of the grid with respect to the filament jointly by two factors, viz: current flow in the grid-filament circuit in response to current flow in the traffic rails, and other means such as a battery, that constantly tend to establish a predetermined potential notwithstanding changes in traffic conditions. The invention further contemplates the employment of direct-current relay means that are responsive to changes in the average value of current flowing in the plate-filament cir-

cuit to thereby assume one condition when the grid potential is the result of the action of both of the above-mentioned factors and to assume a second condition when the grid-filament circuit ceases to be effectively influenced by track current. 55

The grid-filament circuit is, in this instance, also a pick-up circuit and consists here of coil 1 in an inductive relation to the traffic rails, wires 90 and 92, grid G and filament F. It will be evident that this circuit, which may be tuned to resonance at the frequency of a trackway current by means of tuning condenser 142, constitutes one of the factors that controls the potential of the grid with respect to the filament. The other factor that controls this potential is battery 140 which is suitably connected to the grid-filament circuit. 141 is a potentiometer or variable resistance that may be employed in connection with battery 140. The plate-filament circuit is provided with a suitable current source, here indicated by battery 83, and responsive to the influence of the average value of current flowing in said plate-filament circuit are suitable direct-current relay means. 60

Such relay means may take any of the forms known in the art as disclosed for instance in Letters Patent No. 1,791,779 of February 10, 1931 and application Ser. No. 147,403 but it is preferred to employ a direct-current polarized relay as 24 which assumes 65

one condition when the grid potential is the result of the action of both of the before-mentioned factors and to assume a second condition when variations of potential, due to the trackway current, are absent from the grid filament circuit. Specifically, relay 24

controls a polarized armature 30 having a pendulous movement and which swings in one direction when relay 24 assumes one condition and in the other direction when said relay assumes another condition. 85

Relay 24 may also have a neutral armature 28. Relay 24 is biased, in any of the ways known in the art as is fully described and disclosed in Letters Patent No. 1,791,779 of February 10, 1931 and application Ser. No. 147,403, to

assume one condition when direct current of an intermediate value, say a direct current 90

100

of an average value of 0.60, is flowing in the coil of the relay, and to assume a second condition when the current flow is either increased or decreased in value with respect 5 to said intermediate value. In the case here illustrated, relay 24 is biased so that polarized armature 30 will assume the right-hand position, or the position shown in the Fig. 2, when the direct current flowing in 10 the coils of the relay is of an intermediate value and of the proper polarity and will assume the left-hand position, or the position opposite to that shown in Fig. 2, when the direct current is either increased or decreased 15 in value with respect to said intermediate value, notwithstanding that the polarity of the current remains the same. Neutral armature 28 of relay 24 will remain lifted as shown in Fig. 2 at all values of the 20 current except at a very low value, that is, a value much less than the intermediate value. As will be seen, armatures 28 and 30 control a circuit through traffic controlling means 33 which may operate signals 25 and/or brake application devices in a manner well understood. In the present instance, relay 24 is made subject to the influence of variations in the average value of 30 the current in the plate-filament circuit by being included directly in said circuit.

An instance of symmetrical variations produced by a suitable trackway current is indicated in the diagram Fig. 4 and as will be understood, similar variations are thereby 35 induced in the grid-filament circuit which in turn produce similar symmetrical variations in the potential of the grid. In employing the electron tube in the manner disclosed, advantage is taken of the fact that the plate-current grid-voltage characteristic graph of 40 an electron tube does not show a straight line but a pronounced curve at its upper and lower ends as shown in Figs. 3 and 3a. By means of a train-carried source of power such as battery 140, it is possible to so adjust the 45 potential of the grid with respect to the filament that, when no voltage is induced in pick-up coil 1, the operating point of tube E will be at point N at the upper bend, or 50 at point N' at the lower bend of the characteristic curve of Figs. 3 and 3a. If the operating point selected is point N at the upper bend (Fig. 3a) then when no voltage is induced in the pick-up coil the grid potential 55 is represented by E_g and the current in the plate circuit will be represented by I . When an alternating current is induced in the pick-up coil by the current flowing in the traffic rails, and this alternating voltage 60 is impressed between the grid and filament it will produce, during every cycle, approximately equal and opposite variations of potential of the grid with respect to the filament, represented by $+e$ and $-e$, from 65 the potential derived from battery 140. Plot-

ting these variations of potential $+e$ and $-e$ on the curve of Fig. 3a, it is seen that the resultant variations i_1 and i_2 of the plate current are unequal due to the bend of the characteristic curve and since the decrease in the current (i_2) of the plate-filament circuit occasioned by the negative half cycle of the incoming induced voltage exceeds the increase in the current (i_1) of said circuit due to the positive half cycle of the induced voltage, the result is that the average value of the current in the plate-filament circuit is decreased, or an intermediate value of current is established. This action of the symmetrical variations of potential of the grid so occasioned by the rail current therefore produces asymmetrical current impulses or variations of the current in the plate-filament circuit that result in a change in the average value of said current as illustrated by Fig. 4a. Therefore, if I assume that the full or original value of the current supplied by the battery 83 to the plate-filament circuit to be 1.00, then the asymmetrical variations i_1 and i_2 results in an intermediate average value 85 of, let us say, 0.60. With direct-current polarized relay 24 biased in the manner previously described, the polarized armature responds to this change in the average value 90 of the current of the plate-filament circuit by swinging to the right-hand position as shown in Fig. 2. In other words, the alternating rail current having symmetrical variations, or oscillations, induces in the pick-up coil on the train a current having similar 100 variations that create similar symmetrical variations of potential of the grid. These symmetrical variations of grid potential, due to the potential established by battery 140, manifest themselves by creating asymmetrical 105 impulses or variations of plate-filament circuit current with the result that the average value of said current is changed. Relay 24 is responsive to this change in the average 110 value of the current of the plate-filament circuit and thereby effects a change in the position of polarized armature 30 so that it will occupy the position shown in Fig. 2. Conversely, absence of the symmetrical variations of the rail current will permit a current of the value of 1.0 to flow in the plate-filament circuit and armature 30 will therefore swing to the left in Fig. 2.

If the operating point N' (Fig. 3) at the lower bend of the curve is selected, then the induced variations in pick-up coil 1 would produce a large increase and a small decrease in the value of the current of the plate-filament circuit. In such case the original current supplied by battery 83 to the plate-filament circuit, that is, when there is no induced current in the pick-up coil and the potential of the grid is that derived solely from battery 140, will have a low value. This low value is not sufficient to energize relay 24 to 120

overcome the biasing on polarized armature 30 and therefore said armature 30 is held in the left-hand position. When the induced current in pick-up coil 1 creates the increase 5 i_1 at each positive half cycle of the induced current and the decrease i_2 at each negative half cycle in the current of the plate-filament circuit, the result is that the average value of said current is increased. This action, 10 where the symmetrical variations of the induced current result in an increase in the average value of the current of the plate-filament circuit, is illustrated in Fig. 4b. Let us assume that the original value of the current 15 in the plate-filament circuit is 0.20 and that, as the result of the variations of grid potential caused by the induced current, the average value produced is 0.60, then with the direct-current polarized relay biased in 20 the manner previously described, polarized armature 30 will respond to this change in the average value by swinging to the right-hand position.

The means for supplying current to the 25 rails may vary widely and the hereinafter described system will serve as an exemplification thereof. A traffic track indicated by rails 55 and 56 is provided, and this track is divided into blocks, such as blocks A, B and 30 C, as by insulations 3', and on this traffic track traffic normally moves in but one direction, that direction being indicated in Fig. 1 by an arrow. Each block is provided with the common track circuit consisting of a track 35 relay connected across the rails at the ingoing end of the block, and fed by a battery connected across the rails at the outgoing end of the block. Taking block B as an illustration, track relay 148' is connected to rails 55 and 56 at the ingoing end and track battery 155 is connected to the rails at the outgoing end of the block. A second track circuit, which also preferably includes the traffic rails, is provided for each block. This second 40 track circuit supplies a suitable current such as an interrupted or a simple alternating current to the rails. This current has symmetrical variations or oscillations, as illustrated in Fig. 4, and this alternating current cooperates with train-carried apparatus 45 in the manner previously pointed out. This second circuit for a block is controlled by the track relay for the block in advance, and as the circuit is closed only when said track 50 relay is energized, the alternating current is supplied to the rails only under proceed traffic conditions. Specifically, generator 51 supplies alternating current to line wires 52 and 53 and taking the case of block B, transformer 101 supplies current from the line wires to the circuit that feeds the rails. One side of secondary 145 of transformer 101 is connected to rail 56 by wire 146, armature 147 of track relay 148 of block C in advance, contact point 149 and wire 150. The other side

of secondary 145 is connected to rail 55 by wire 152, resistance 153 and wire 154, track battery 155 being connected between wires 150 and 154 and to the latter through impedance 157 and wire 156. Impedance coil 157 is to choke back the flow of alternating current through battery 155, and resistance 153 is to prevent secondary 145 from short-circuiting the battery and to limit the flow of current from secondary 145 when the rails of the block are shunted by a train. 70

Whenever block C is unoccupied, relay 148 will close the circuit from secondary 145 to the rails of block B in the rear, and a train entering such block B will have its train-carried apparatus controlled by the alternating current flowing in the traffic rails. Such a train entering block B also deenergizes track relay 148' and this will open the alternating current circuit for block A in the rear of block B. If under these circumstances a train should enter block A, its train-carried apparatus would be uninfluenced by an alternating current. Likewise, should a train enter block B behind the first-mentioned train, then the first train will have shunted the alternating current so that said second train in block B will receive no alternating current. 80

Should a train equipped with the apparatus of Fig. 2 enter block B of Fig. 1, traveling in the direction indicated by the arrow, and block C in advance, as well as block B, be unoccupied by any other train, then alternating current supplied by transformer 101 flows in the rails of block B to induce a current in coil 1 on the train. This induced current having oscillations similar to the alternating rail current causes positive and negative swings of the potential of grid G with respect to the original potential derived from battery 140, and as previously pointed out these swings of potential, altho symmetrical, effect through asymmetrical impulses, a change in the average value of the current in the plate-filament circuit by either reducing it from a high value to an intermediate value as in the case where the point N is selected, or by increasing it from a low value to the intermediate value, as in the case where point N' is selected. This change in the value of the current in the plate-filament circuit causes the polarized armature to swing to the right-hand position, and as shown in Fig. 2 this closes the circuit to brake controlling and signaling device 33 to thereby hold the brakes inoperative and to display a proceed signal on the train. 100

But if block C is occupied and block B unoccupied as the train enters block B, then the flow of the alternating current from transformer 101 to the rails of block B is cut off at contact 149 of track relay 148 of block C. No current will then be induced in pick-up coil 1 of the train entering block 110

B, with the result that grid G of tube E has its potential with respect to the filament controlled only by battery 140, and the current in the plate-filament circuit assumes its original value, which will be the high value if point N is selected, and which will be the low value if point N' is selected. Polarized armature 30 therefore swings to the left-hand position in response to the change in the value 10 of the current in the plate-filament circuit from the intermediate value back to the high or to the low value as the case may be, and by swinging to the left-hand position, opens the circuit to device 33 to thereby control the 15 brake controlling means and to display a danger signal on the train. Again, if block B is already occupied by a train when a second train enters the block at the ingoing end, it is evident that the alternating current supplied by transformer 101 to the rails of block B will be shunted away from the second train by the wheels and axles of the first train, and that there will be no current induced in the 20 pick-up coil of the second train. Consequently, polarized armature 30 of the second train will assume the left-hand position in response to the absence of the alternating rail current.

I claim:

1. A continuously acting train control system including: traffic rails arranged in blocks, a train, a train-carried electron tube having a plate, a grid and a filament, a train-carried plate-filament circuit having a current source that charges said circuit with current of a given average value, direct-current relay means responsive to the influence of the change in the average value of current flowing in the plate-filament circuit, that is produced by current impulses, created in said current, the influence of which is asymmetrical with respect to the original average value of said current, means associated with the electron tube to create said asymmetrical current impulses in response to symmetrical variations in the potential of the grid with respect to the filament, and a trackway current source that supplies to said rails, under proceed traffic conditions, a current that by its influence produces symmetrical variations in the potential of the grid.

2. A continuously acting train control system including: traffic rails arranged in blocks, a train, a train-carried electron tube having a plate, a grid and a filament, a train-carried plate-filament circuit having a current source that charges said circuit with current of a given average value, direct-current relay means responsive to the influence of change in the average value of current flowing in the plate-filament circuit, that is produced by current impulses, created in said current, the influence of which is asymmetrical with respect to the original average value of said current, means associated with the elec-

tron tube to create said asymmetrical current impulses in response to symmetrical variations in the potential of the grid with respect to the filament consisting of (1) a train-carried grid-filament circuit continuously responsive to the influence of symmetrical variations of the current in the rails to thereby continuously reflect traffic conditions thereof and (2) additional means constantly tending to establish a predetermined potential of the grid notwithstanding changes in traffic conditions; and a trackway current source that supplies to said rails, under proceed traffic conditions, a current that by its influence produces symmetrical variations of potential in the train-carried grid-filament circuit.

3. A continuously acting train control system including: traffic rails arranged in blocks, a train, a train-carried electron tube having a plate, a grid and a filament, a train-carried plate-filament circuit having a current source that charges said circuit with current of a given average value, a direct-current polarized relay responsive to the influence of the change in the average value of current flowing in the plate-filament circuit, that is produced by current impulses, created in said current, the influence of which is asymmetrical with respect to the original average value of said current, means associated with the electron tube to create said asymmetrical current impulses in response to symmetrical variations in the potential of the grid with respect to the filament, and a trackway current source that supplies to said rails, under proceed traffic conditions, a current that by its influence produces symmetrical variations in the potential of the grid.

4. A continuously acting train control system including: traffic rails arranged in blocks, a train, a train-carried electron tube having a plate, a grid and a filament, a train-carried plate-filament circuit having a current source that charges said circuit with current of a given average value, a direct-current polarized relay responsive to the influence of the change in the average value of current flowing in the plate-filament circuit, that is produced by current impulses, created in said current, the influence of which is asymmetrical with respect to the original average value of said current, means associated with the electron tube to create said asymmetrical current impulses in response to symmetrical variations in the potential of the grid with respect to the filament consisting of (1) a train-carried grid-filament circuit continuously responsive to the influence of symmetrical variations of the current in the rails to thereby continuously reflect traffic conditions thereof and (2) additional means constantly tending to establish a predetermined potential of the grid notwithstanding changes in traffic conditions; and a trackway current source that supplies to

said rails, under proceed traffic conditions, a current that by its influence produces symmetrical variations of potential in the train-carried grid-filament circuit.

5 5. A continuously acting train control system including: traffic rails arranged in blocks, a trackway current source that supplies to said rails, under proceed traffic conditions, a current that by its influence produces symmetrical variations of potential in a train-carried grid-filament circuit, a train, a train-carried electron tube having a plate, a grid and a filament, the potential of the grid being controlled jointly by two factors 10 15 consisting of the following means: (1) a train-carried grid-filament circuit continuously responsive to the influence of the current in the rails to thereby continuously reflect traffic conditions thereof and (2) train-carried means constantly tending to establish a predetermined potential notwithstanding changes in traffic conditions; a train-carried plate-filament circuit, a current source that charges said circuit with current of a 20 25 given value, the average value of the current flowing in said plate-filament circuit being determined by the joint control of said two factors, and direct-current relay means responsive to a change in the average value of 30 35 the current flowing in the plate-filament circuit to assume one condition when the grid potential is the result of the action of both factors and to assume a second condition when variations of potential are absent from the grid-filament circuit.

6. A continuously acting train control system including: traffic rails arranged in blocks, a trackway current source that supplies to said rails, under proceed traffic conditions, a current that by its influence produces symmetrical variations of potential in a train-carried grid-filament circuit, a train, a train-carried electron tube having a plate, a grid and a filament, the potential of the grid being controlled jointly by two factors consisting of the following means: (1) a train-carried grid-filament circuit continuously responsive to the influence of the current in the rails to thereby continuously reflect traffic conditions thereof and (2) train-carried means constantly tending to establish a predetermined potential notwithstanding changes in traffic conditions; a train-carried plate-filament circuit, a current source that charges said circuit with current of a given value, the average value of the current flowing in said plate-filament circuit being determined by the joint control of said two factors, and a direct-current polarized relay responsive to a change in the average value of the current flowing in the plate-filament circuit and having an armature that assumes one position when the grid potential is the result of the action of both factors and that assumes a second position when variations

of potential are absent from the grid-filament circuit.

7. A continuously acting train control system including: traffic rails arranged in blocks, a trackway current source that supplies to said rails, under proceed traffic conditions, a current that by its influence produces symmetrical variations of potential in a train-carried grid-filament circuit, a train, a train-carried electron tube having a plate, a grid and a filament, the potential of the grid being controlled jointly by two factors consisting of the following means: (1) a train-carried grid-filament circuit continuously responsive to the influence of the current in the rails to thereby continuously reflect traffic conditions thereof and (2) train-carried means constantly tending to establish a predetermined potential notwithstanding changes in traffic conditions; a train-carried plate-filament circuit, a current source that charges said circuit with current of a given value, the average value of the current flowing in said plate-filament circuit being determined by the joint control of said two factors, a direct-current polarized relay responsive to a change in the average value of the current flowing in the plate-filament circuit, and an armature associated with said polarized relay that moves in one direction when the grid potential is the result of the action of both factors and that moves in the other direction when variations of potential are absent from the grid-filament circuit. 70 75 80 85 90 95

8. A continuously acting train control system including: traffic rails arranged in blocks, a trackway current source that supplies to said rails, under proceed traffic conditions, a current that by its influence produces symmetrical variations of potential in a train-carried grid-filament circuit, a train, a train-carried electron tube having a plate, a grid and a filament, the potential of the grid being controlled jointly by two factors consisting of the following means: (1) a train-carried grid-filament circuit continuously responsive to the influence of the current in the rails to thereby continuously reflect traffic conditions thereof and (2) train-carried means constantly tending to establish a predetermined potential notwithstanding changes in traffic conditions; a charged train-carried plate-filament circuit, the average value of the current flowing in said plate-filament circuit being determined by the joint control of said two factors, a direct-current polarized relay responsive to a change in the average value of the current flowing in the plate-filament circuit, and an armature having a pendulous movement associated with said polarized relay that swings in one direction when the grid potential is the result of the action of both factors and that swings in the other direction when variations of po- 100

tential are absent from the grid-filament circuit.

9. A continuously acting train control system including: traffic rails arranged in blocks, a train, a train-carried electron tube having a plate, a grid and a filament, a train-carried plate-filament circuit having a current source that charges said circuit with current of a given average value, direct-current relay means responsive to the influence of the change in the average value of current flowing in the plate-filament circuit, that is produced by current impulses; created in said current, the influence of which is asymmetrical with respect to the original average value of said current, means to create said asymmetrical current impulses in response to symmetrical variations in the potential of the grid with respect to the filament including: (1) a train-carried grid-filament circuit continuously responsive to the influence of symmetrical variations of the current in the rails to thereby continuously reflect traffic conditions and (2) a power source connected to the grid-filament circuit, said power source constantly tending to establish a predetermined potential of the grid notwithstanding changes in traffic conditions; and a trackway current source that supplies to said rails, under proceed traffic conditions, a current that by its influence produces symmetrical variations of potential in the train-carried grid-filament circuit.

10. A continuously acting train control system including: traffic rails arranged in blocks, a train, a train-carried electron tube having a plate, a grid and a filament, a train-carried plate-filament circuit having a current source that charges said circuit with current of a given average value, a direct-current polarized relay responsive to the influence of the change in the average value of current flowing in the plate-filament circuit, that is produced by current impulses, created in said current, the influence of which is asymmetrical with respect to the original average value of said current, means to create said asymmetrical current impulses in response to symmetrical variations in the potential of the grid with respect to the filament including: (1) a train-carried grid-filament circuit continuously responsive to the influence of symmetrical variations of the current in the rails to thereby continuously reflect traffic conditions and (2) a power source connected to the grid-filament circuit, said power source constantly tending to establish a predetermined potential of the grid notwithstanding changes in traffic conditions; and a trackway current source that supplies to said rails, under proceed traffic conditions, a current that by its influence produces symmetrical variations of potential in the train-carried grid-filament circuit.

11. A continuously acting train control

system including: traffic rails arranged in blocks, a trackway current source that supplies to said rails, under proceed traffic conditions, a current that by its influence produces symmetrical variations of potential in a train-carried grid-filament circuit, a train, a train-carried electron tube having a plate, a grid and a filament, the potential of the grid being controlled jointly by two factors including the following means: (1) a train-carried grid-filament circuit continuously responsive to the influence of the current in the rails to thereby continuously reflect traffic conditions thereof and (2) a power source connected to the grid-filament circuit, said power source constantly tending to establish a predetermined potential of the grid notwithstanding changes in traffic conditions; a train-carried plate-filament circuit, a current source that charges said circuit with current of a given value, the average value of the current flowing in said plate-filament circuit being determined by the joint control of said two factors, and direct-current relay means responsive to a change in the average value of the current flowing in the plate-filament circuit to assume one condition when the grid potential is the result of the action of both factors and to assume a second condition when variations of potential are absent from the grid-filament circuit.

12. A continuously acting train control system including: traffic rails arranged in blocks, a trackway current source that supplies to said rails, under proceed traffic conditions, a current that by its influence produces symmetrical variations of potential in a train-carried grid-filament circuit, a train, a train-carried electron tube having a plate, a grid and a filament, the potential of the grid being controlled jointly by two factors including the following means: (1) a train-carried grid-filament circuit continuously responsive to the influence of the current in the rails to thereby continuously reflect traffic conditions thereof and (2) a power source connected to the grid-filament circuit, said power source constantly tending to establish a predetermined potential of the grid notwithstanding changes in traffic conditions; a train-carried plate-filament circuit, a current source that charges said circuit with current of a given value, the average value of the current flowing in said plate-filament circuit being determined by the joint control of said two factors, and a direct-current polarized relay responsive to a change in the average value of the current flowing in the plate-filament circuit and having an armature that assumes one position when the grid potential is the result of the action of both factors and that assumes a second position when variations of potential are absent from the grid-filament circuit.

13. A continuously acting train control system including: traffic rails arranged in blocks, a trackway current source that supplies to said rails, under proceed traffic conditions, a current that by its influence produces symmetrical variations of potential in a train-carried grid-filament circuit, a train, a train-carried electron tube having a plate, a grid and a filament, the potential of the grid being controlled jointly by two factors including the following means: a train-carried grid-filament circuit continuously responsive to the influence of the current in the rails to thereby continuously reflect traffic conditions thereof and (2) a power source connected to the grid-filament circuit, said power source constantly tending to establish a predetermined potential of the grid notwithstanding changes in traffic conditions; 15 a train-carried plate-filament circuit, a current source that charges said circuit with current of a given value, the average value of the current flowing in said plate-filament circuit being determined by the joint control of said two factors, a direct-current polarized relay responsive to a change in the average value of the current flowing in the plate-filament circuit, and an armature associated with said polarized relay that moves in one direction when the grid potential is the result of the action of both factors and that moves in the other direction when variations of potential are absent from the grid-filament circuit.

33 14. A continuously acting train control system including: traffic rails arranged in blocks, a trackway current source that supplies to said rails, under proceed traffic conditions, a current that by its influence produces symmetrical variations of potential in a train-carried grid-filament circuit, a train, a train-carried electron tube having a plate, a grid and a filament, the potential of the grid being controlled jointly by two factors including the following means: (1) a train-carried grid-filament circuit continuously responsive to the influence of the current in the rails to thereby continuously reflect traffic conditions thereof and (2) a power source connected to the grid-filament circuit, said power source constantly tending to establish a predetermined potential of the grid notwithstanding changes in traffic conditions; a charged train-carried plate-filament circuit, the average value of the current flowing in said plate-filament circuit being determined by the joint control of said two factors, a direct-current polarized relay responsive to a change in the average value of the current flowing in the plate-filament circuit, and an armature having a pendulous movement associated with said polarized relay that swings in one direction when the grid potential is the result of the action of both factors and that swings in the other direction

when variations of potential are absent from the grid-filament circuit.

15. A continuously acting train control system including: a traffic track composed of rails arranged in blocks, a train, a train-carried electron tube detector having a plate, a grid and a filament, a plate-filament circuit, a current source that charges said circuit with current of a given average value, direct-current relay means responsive to the influence of a change in the average value of current flowing in the plate-filament circuit, a grid-filament circuit responsive to the influence of current flowing in the rails of the traffic track, a power source connected to the grid-filament circuit tending at all times to establish a certain potential on the grid with respect to the filament, and a trackway current source to supply, under proceed traffic conditions, current of varying potential to the rails to thereby exert an influence to establish, through the grid-filament circuit, symmetrical variations in potential of the grid, said symmetrical variations in conjunction with the power source connected to the grid-filament circuit producing asymmetrical variations in the current of the plate-filament circuit to thereby vary the average value of current flowing in said plate-filament circuit.

16. A train control system including: a traffic track arranged in blocks, a train, a train-carried electron tube having a plate, a filament and a grid, a plate-filament circuit, a current source that charges said circuit with current of a given average value, direct-current relay means responsive to the influence of a change in the average value of current flow in the plate-filament circuit, and means to vary the average value of current flow in the plate-filament circuit by symmetrical variations in the potential of the grid with respect to the filament including: a traffic-controlled trackway source of power and a train-carried source of power non-responsive to traffic conditions to jointly influence the potential of the grid.

Signed at Pittsburgh, in the county of Allegheny and State of Pennsylvania, this 13th day of June, 1929.
